ABSTRACT OF THE DISCLOSURE

A feedback circuit is described in which output signals from a pair of equalizer tap circuits are added together to provide an equalized output signal. During an initial start-up interval the equalizer output signal is forced to zero by feedback circuits in each tap circuit.

A second feedback loop senses the equalized output signal to correct the reference level supplied to the tap circuit feedback circuits if a non-zero output is present.

FIELD OF THE INVENTION

This invention relates to negative feedback systems and particularly to a negative feedback system in which two loosely coupled feedback loops cooperate to bring an output signal to a desired value.

BACKGROUND OF THE INVENTION

When a multifrequency signal which includes a series of individual data or symbol bits is transmitted through a bandwidth-limited medium, different frequency components in this signal may be delayed and attenuated different amounts so that components from more than one of the individual symbol bits may coincidentally arrive at a signal receiver thereby causing intersymbol interference. One device used to equalize a received signal distorted by intersymbol interference is a transversal filter equalizer.

The transversal filter equalizer is a time-domain device in which one or more equalization signals each equal to a multiple of the received signal, displaced in time, are added to the received signal to provide an equalized output signal. A plurality of multipliers is employed to provide the received signal multiples.

Automatic and adaptively adjusted transversal filter equalizers employ circuits to operate on the equalized output signal to derive adjusting signals for setting the values of the multiples for each of the plurality of multipliers. At the beginning of a transmission sequence, each multiplier has an arbitrary multiplication factor. To insure that the equalization signals which are initially added by these multipliers do not prolong or render impossible adaptive or automatic equalization, it has been found best to set each of the multipliers to a multiplication factor of zero.

Some automatic and adaptive transversal filter equalizers employ discrete value resistor attenuators in combination with inverting amplifiers as multipliers. The multiplying factors of these multipliers may be varied by using relays or transistors to physically switch resistors in the voltage dividers. At the start of automatic or adaptive adjusting of the transversal filter equalizer, the multiplying factors are set to zero by switching appropriate discrete value resistors in the attenuators. In this way, it is assured that arbitrary equalization signals are not added to the received signal. As equalization progresses, the multiplying factors are positively or negatively increased from zero in accordance with the adjusting signals to provide the proper equalization signals to equalize the received signal.

When tap multipliers are employed which utilize voltage-controlled impedance devices, a preset voltage signal is applied to the multiplier to set the multiplication factor initially to zero. When the voltage-controlled impedance is a Field Effect Transistor the preset voltage level is typically one quarter of a volt. The preset voltage signal is employed in some tap multipliers as a reference signal at a summing point of a feedback loop. In a multitap equalizer, each of the tap multipliers is normally constructed on individual plug-in boards. The preset voltage is generated by a circuit on a separate board. It has been found that even with properly designed preset tap multiplier circuits, reset voltage signal errors due to component variations and intra- and interboard lead impedance variations create nonzero multiplier output values.

The multiplier output values can be brought to zero by adjusting the reset voltage source. This, however, requires factory adjustment for each equalizer. A field adjustment would also be required each time a reference voltage circuit board were replaced.

BRIEF DESCRIPTION OF THE INVENTION

In the present invention a tap multiplier circuit, including an amplifier, is built on a first circuit board. A signal controllable reference voltage source is built on a second circuit board. An external wire connects the reference voltage source to the amplifier in the tap multiplier. An output condition sensor responsive to the output of the tap multiplier feeds a control signal back to adjust the reference voltage source.

In one embodiment, a second tap multiplier circuit, built on a second circuit board, is connected by a second external wire to the reference voltage source. The output condition sensor is responsive to the sum of the outputs from the two tap multipliers. In this embodiment, output signals from both the taps are brought to zero together.

DESCRIPTION OF THE DRAWING

The sole figure shows in schematic form a circuit embodying the further principles of this invention.

DETAILED DESCRIPTION

A feedback circuit is often employed to generate a voltage having a known D-C value. The heart of such a circuit is usually a high-gain differential amplifier. Typically, a voltage is applied from a reference voltage source to the noninverting terminal of the amplifier. A standard voltage is applied through a resistor to an inverting input terminal of the amplifier. A resistor is usually connected between an output and the inverting input of the amplifier.

In the circuit shown in the figure, output signals from two conventional feedback circuits are added together. Each of a pair of circuits 21a and 21b, enclosed in dashed lines in the figure, is an equalizer tap circuit. The circuitry enclosed in box 22 forms a summing amplifier.

Each of the tap circuits 21a or 21b when connected to a summing amplifier such as summing amplifier 22 forms a tap multiplier circuit similar to one disclosed in the copending application of E. Port, Ser. No. 663,148, filed Aug. 24, 1967, now U.S. Pat. 3,475,601. The summing amplifier 22, shown in the figure, is common to both the circuits 21a and 21b. Connected in this way, an output signal is provided which is identical to the signal which would be generated by adding the signals from two complete tap multiplier circuits.

During an initial start-up interval, voltage source 23 is enabled to provide both a voltage reference signal and a standard D-C voltage for feedback circuits in tap circuits 21a and 21b which set the output signal from the summing amplifier 22 to zero. In accordance with this invention, a lead 24 and a resistor 26 complete a second

feedback loop by feeding the output signal from the summing amplifier 22 back to control the voltage reference signal supplied to the tap circuits 21a and 21b.

In normal operation, terminals 27a and 27b of the tap circuits 21a and 21b, respectively, are connected to taps of a delay line of a transversal filter equalizer. A received data signal from a source, not shown, propagating down the delay line impresses time delayed replicas of the received signal upon each of the terminals 27a and 27b. The delayed replicas of the received data signal on the terminals 27a and 27b are multiplied by values determined upon integration of differential adjusting signals applied to adjusting input terminals 28a and 28b, respectively. The differential adjusting signals are derived by equipment, not shown, in response to the output signal from summing amplifier 22.

The received replicas on the terminals 27a and 27b are normally passed by inhibit gates 29a and 29b through resistors 31a and 31b to drain electrodes 32a and 32b of field effect transistors 33a and 33b, respectively. Source electrodes 34a and 34b of the field effect transistors 33a and 33b are connected at an input terminal 36 of an inverting operational amplifier 37 to maintain the source electrodes 34a and 34b of the field effect transistors 33a and 33b at a virtual ground potential. The voltage appearing at the output of amplifier 37 is proportional to the sum of the voltages across the source and drain of field effect transistors 33a and 33b divided by the respective source-to-drain impedances. Since the voltage between the source and drain of field effect transistors 33a and 33b are directly related to the signal on terminals 27a and 27b, respectively, the output signal from amplifier 37 is proportional to the sum of the products of the signals applied to terminals 27a and 27b and the source-to-drain conductance of field effect transistors 33a and 33b, respectively.

Since the amplifier 37 inverts signals applied to input terminal 36, one is able to multiply the signals appearing on terminals 27a and 27b by either positive, zero, or negative values, by adding a signal directly proportional to the signal appearing on terminals 27a and 27b to the output signal from amplifier 37. The signal at the output of amplifier 37 can then be adjusted so that the sum of the signals can be positive, negative, or zero. To this end, resistors 38a and 38b are connected from the drains 32a and 32b of field effect transistors 33a and 33b, respectively, to inverting input terminal 39 of amplifier 41. Resistor 42 is provided to apply the signal from amplifier 37 to input 39 of amplifier 41 so that the signal appearing on output terminal 43 thereof is proportional to the sum of the products of the signal appearing on the terminals 27a and 27b and the source-to-drain conductance of field effect transistors 33a and 33b, respectively. As has been pointed out, the output signal on terminal 43 can be set to zero or to positive or negative multiples of the input signal on terminals 27a and 27b by appropriate adjustment of the source-to-drain impedance of field effect transistors 33a and 33b.

The source-to-drain impedance of the field effect transistors 33a and 33b are adjusted by varying the gate-to-source voltage thereof. Inverting operational amplifiers 44a and 44b shunted by capacitors 46a and 46b are employed as Miller integrators to control the gate-to-source voltages of field effect transistors 33a and 33b, respectively. A Miller integrator is a high-negative gain amplifier with capacitive feedback. High-impedance voltage dividers, comprising resistors 47a and 47b and 48a and 48b, each having typical values of 150K ohms and joined at center positions 49a and 49b, respectively, are connected between drains 32a and 32b of the field effect transistors 33a and 33b and ground. The center positions 49a and 49b of the voltage dividers are connected to non-inverting input terminals 51a and 51b of the amplifiers 44a and 44b, respectively. Voltage variations at drains 32a and 32b of field effect transistors 33a and 33b are

therefore fed back to amplifiers 44a and 44b, respectively, and therefore to the gates of field effect transistors 32a and 32b linearizing the source-to-drain current versus source-to-drain voltage characteristics of the field effect transistors. The inverting inputs of amplifiers 44a and 44b therefore are always at a voltage equal to one-half the voltage across the respective field effect transistors 33a and 33b. This maintains the gate-to-source A-C voltage of field effect transistors 33a and 33b at one-half the respective drain-to-source A-C voltages. For a more complete discussion of this linearizing technique, see "Circuit Applications of the Field Effect Transistor," published in the March 1962 issue of "Semiconductor Products," pp. 31 and 32.

It should be noted that sources 34a and 34b of field effect transistors 33a and 33b are maintained at a virtual ground by amplifier 37 so that the voltage dividers may be returned directly to ground to linearize field effect transistors 33a and 33b. Alternately, the current flowing through field effect transistors 33a and 33b and resistors 38a and 38b may be directly subtracted in a differential amplifier having common mode rejection. However, the common mode signal, which would also vary the voltage across field effect transistors 33a and 33b would not be compensated for by the ground returned voltage-divider feedback. The result is that the common mode signal would have to be made small with respect to the voltage across field effect transistors 33a and 33b.

The differential adjusting signals on terminals 28a and 28b are applied to amplifiers 44a and 44b through resistors 52a and 52b, respectively. In normal operation, the replica signals applied to input terminals 27a and 27b are multiplied by a factor proportional to the source-to-drain conductances of the field effect transistors 33a and 33b which are controlled by the integral of the differential adjusting signal applied to the terminals 28a and 28b.

The initial value of source-to-drain impedances of field effect transistors 33a and 33b and therefore the initial value by which the replica signals on terminals 27a and 27b are multiplied, is set when an initialization pulse is applied to an input terminal 55 of gate 53 from a source, not shown. The initialization pulse, extracted from the received data signal by circuits, not shown, indicates the beginning of a transmission requiring adjustment of the equalizer circuits.

The gate 53 applies a voltage +V to inhibit inputs 54a and 54b of inhibit gates 29a and 29b, respectively, to block the delayed replica so that no voltage appears across the resistors 31a and 31b, respectively. Resistors 56a and 56b are connected between the inhibit terminals 54a and 54b, respectively, and the drains 32a and 32b of the field effect transistors 33a and 33b. Resistors 56a and 56b functionally replace resistors 31a and 31b during the preset sequence. The voltage applied to the inhibit terminals 54a and 54b is of a standard amplitude so that with resistors 56a and 56b in series with the source-to-drain impedances of the field effect transistors, the voltages appearing at the drains 32a and 32b of the field effect transistors are determined by the source-to-drain impedances of the field effect transistors. It should be noted that the source-to-drain impedances of the field effect transistors 33a and 33b are effectively in parallel with the fixed value resistors 38a and 38b.

The voltage from gate 53 is also applied through resistors 57a and 57b to saturate normally off transistors 58a and 58b. Saturation of transistors 58a and 58b applies voltage from the voltage source 23 to the inverting inputs of operational amplifiers 44a and 44b, respectively. The low impedance applied to the inverting input of operational amplifiers 44a and 44b through saturated transistors 58a and 58b, respectively, from voltage source 23 overrides signals which might be applied at the terminals 28a and 28b, respectively, through resistors 52a and 52b by bringing the summing point of the Miller integrators, which include amplifiers 44a and 44b, capacitors 46a and

46b and resistor 52a and 52b to a low impedance condition. The noninverting inputs of operational amplifiers 44a and 44b become the summing points for a negative feedback loop which includes amplifiers 44a and 44b and field effect transistors 33a and 33b, respectively. It should be noted that the inversion necessary for negative feedback is supplied by field effect transistors 33a and 33b. Resistors 47a and 47b and 48a and 48b in the voltage dividers drive the amplifiers 44a and 44b, respectively, to vary the gate voltage of field effect transistors 33a and 33b until the voltage at the drains thereof are essentially twice the voltages supplied by voltage source 23. By forcing the drains to this voltage while the reference voltage from gate 53 is fed to resistors 56a and 56b, the feedback loop forces the field effect transistors to assume specific resistance values. The low impedance output of the amplifiers 44a and 44b charge capacitors 46a and 46b to store the voltage applied to the gates of field effect transistors 33a and 33b.

When the preset signal is removed returning the circuit to normal operation, the gate voltages of field effect transistors 33a and 33b are one-half source-to-drain voltages increased by the voltage across the capacitors 46a and 46b. As differential adjusting signals are received on terminals 28a and 28b and integrated by capacitors 46a and 46b, the source-to-drain impedances of the field effect transistors 33a and 33b are varied accordingly.

When the voltage source 23 is on a separate circuit board from the tap circuits 21a and 21b, current flowing in a lead 59 causing a voltage drop across the lead impedance is shown as a lumped value R_L . It should be noted that current must flow in this lead so that base current can flow to saturate transistors 58a and 58b. The amount of current flowing in the lead is determined by the value of the resistors 57a and 57b. As the number of tap circuits is varied, the current flowing through lead 59 will also vary. Because of the limited operating range of present field effect transistors, the voltage supplied by voltage source 23 is typically 250 millivolts. Therefore, a few millivolts drop in the lead 59 will cause unacceptable errors. To compensate for this, and for component tolerances in voltage source 23, the voltage source 23 includes resistor 26 having a first end connected to a center tap of a voltage divider including voltage resistors 61 and 62. The voltage divider is connected between +V and ground. The center tap is also connected to the noninverting terminal of an amplifier 63. These three resistors 26, 61, and 62, together with resistors 64 and 66 determine the output voltage of voltage source 23. With the opposite end of resistors 26 grounded, the proper voltage is supplied by the voltage source 23.

The lead 24 connects the output terminal 43 of the summing amplifier circuit 22 to the opposite end of resistor 26. Therefore, if the voltage appearing at terminal 43 is zero volt, no signal is fed back. If, however, the voltage drop across R_L , or inexact component values in

23, drives the voltage at terminal 43 to a nonzero value, a signal is fed back to alter the reference voltage supplied by voltage source 23 to the feedback circuits in tap circuits 21a and 21b.

It should be understood that the above-described arrangements are illustrative of the application of the principles of the invention. Numerous other arrangements may be devised by those skilled in the art without departing from the spirit and scope of the invention.

What is claimed is:

1. A system in which signals from a plurality of analog multipliers are added together to provide a sum signal; each of said analog multipliers being initially set to a predetermined value upon application of a reference signal from a reference signal source; said system characterized by:

means responsive to said sum signal for adjusting said reference signal source.

2. The system as described in claim 1 in which: each of said multipliers includes a field effect transistor having gate, source and drain terminals for providing a variable impedance between said source terminal and said drain terminal; said reference signal source also supplies a standard voltage;

said system also includes:

means for applying said standard voltage to said drain terminal of each of said field effect transistors; and

amplifier means for applying said reference signal to said gate terminal of each of said field effect transistors.

3. The system defined in claim 2 in which:

said amplifier means includes a capacitor for storing said adjusted reference signal.

4. The system as defined in claim 3 in which:

said means for applying said standard voltage includes a plurality of resistors, each of said plurality of resistors forming a voltage divider with one of said field effect transistors.
